UNITED STATES PATENT OFFICE.

JOHN G. BUTLER, OF AUGUSTA, GEORGIA.

APPARATUS FOR PLAYING DUPLICATE WHIST.

SPECIFICATION forming part of Letters Patent No. 514,302, dated February 6, 1894.

Application filed March 29, 1893. Serial No. 468,128. (No model.)

To all whom it may concern:

Be it known that I, JOHN G. BUTLER, of Augusta, in the county of Richmond and State of Georgia, have invented a new and useful Improvement in Apparatus for Playing Duplicate Whist, of which the following is a full, clear, and exact description.

The object of my invention is to provide a convenient, attractive and improved device, apparatus or tray, for receiving and preserving the different "hands" or cards as they are played, so that the game such as "whist," "euchre," &c., may be duplicated by playing the "hands" over again, either by the same 5 partners or by transferring the hands intact to opponents.

The use of a special device, apparatus or tray for this purpose, upon which my invention is an improvement, will be best explained by the following statement.

The game of "whist" as above stated, may be thus duplicated, but in playing the cards upon the table and afterward transferring them, mistakes are liable to occur, and if this be avoided by attaching the four "hands" to the sides of a square of pasteboard,—the simplest and rudest device for which different improved devices or trays have been substituted,—the under cards are nevertheless liable to become exposed by the cards getting displaced, unless the trouble be taken to turn over the cards of every "trick" as soon as played. The "hands" are usually picked up and slipped under a rubber band fastened on the pasteboard and should one of these bands break it cannot be replaced without some delay of the game.

My invention is designed to obviate, in a most efficient manner, these objections and facilitate the play, provide a near receptacle for each "hand" as it is played, and to preserve the "hands," as played, for any length of time and insure a transfer of the "hands" to the proper players without the possibility of mistake.

My invention consists of a light tray of metal, wood, paper or other suitable material, in the form of a cross having a raised edge or border deep enough to contain each "hand" and prevent the cards from slipping off the tray as they are played, or exposing the under cards. The "hands" are played into

small and distinctly separated receptacles at the extremities of the branches of the cross, one of which is placed in front of each player 55 and the cards are retained in their respective receptacles by endless elastic bands held in slots in the edge or border of the tray. The backs, or farther sides from the players, of these receptacles, constituting the mouths of 60 said receptacles, are not entirely closed but have projections, studs or offsets which confine the cards in a given direction, but at the same time allow the admission of the fingers so that the cards may be readily extracted 65 from their receptacles. The center portion of the tray is used to hold the checks or counters, or pegs serving as counters and fitting into suitable holes in the tray, may be used, if desired, in scoring the game.

In playing "duplicate whist" with the tray or apparatus, when the cards of one deal have been played, the "hand" of each player is in the receptacle or pocket nearest to him and is then turned over and confined or secured 75 therein by an endless elastic strap or other suitable means, which each player slips over the center of the cards and the pocket into which they have been played. This elastic strap, is brought in contact with the cards, 80 compressing them, by passing through or across a couple of slots or depressions in the border at opposite sides of each branch of the cross-shaped tray. The tray is then put aside and another tray and pack of cards are 85 similarly disposed of until any desired number have been used, when the trays are again placed on the table, one by one, and the cards in them played over again. If there are only two players, each player takes the previous 90 "hand" of his opponent, and if there are four players each player takes the "hand" previously played by the opponent on his right. In order to insure each player getting the correct "hand," one branch of each cross-shaped tray has a constant mark of any suitable kind, which during the first series, is placed in front of the same player and during the second series of games is placed in front 95 of his opponent. One other branch of each cross has a distinctive mark for the "lead" and each cross should be numbered on the under side for record with the score.

Reference is to be had to the accompanying

drawings forming a part of this specification, in which similar letters of reference indicate corresponding parts in both figures.

Figure 1 is a perspective view of the most 5 approved form of my improved tray or device; and Fig. 2 is a similar view of a slight modification of the same.

A, indicates the cross shaped tray and b, the 10 card receptacles, pockets or compartments formed by the distinct and separated branches thereof. One form of projections, stops or offsets is shown in Fig. 1 at c, to prevent the 15 cards from slipping forward toward the center d of the tray. A border e is shown running entirely around the cross, thus making a shallow tray and in connection with the 20 projections, stops or offsets c completing the four card receptacles b and the center compartment or well d to hold the counters. The end- 25 less elastic straps hereinbefore referred to are indicated by f. These straps are stretched across the card receptacles and pass through slots or depressions g in the border e, which slots serve to hold them in place. The con- 30 stant mark used opposite one branch of each tray, to insure each player getting the correct "hand," is shown at h, while i, indicates the 35 mark for the "lead."

In Fig. 2 of the drawings, substantially the 30 same construction is shown as in Fig. 1, but this form will add somewhat to the strength and stiffness of the tray and provides a larger center compartment d.

The raised border e need not run entirely 35 around either form of tray, but adds stiffness by so doing. If not running entirely around, it may be confined to the ends of the four 40 branches of the cross-shaped tray, and any suitable form of projections, stops or offsets c' may be used, as also any suitable mark for 45 indicating the "lead."

I do not claim as my invention the exchanging or providing for an exchange of "hands" and playing them over again, which is old, 45 nor yet a marked or figured board and elastic straps; neither, in the abstract, a tray for the game of duplicate whist, provided with four holders arranged to retain the several 50 "hands" of play by themselves in the game 55 of duplicate whist, but the improved cross-shaped tray or apparatus hereinbefore described possesses many advantages which 60 characterize it with special novelty and utility. Thus the cards can be played directly 55 upon or into those parts or distinct and separated receptacles formed by the branches of the cross-shaped tray in which they are to be ultimately confined, and thus played they stay in place and expose only the cards of the previous "trick," which by the rule of whist 65 every player has the right to see, and thus is avoided the necessity of turning over every "trick" after it is played, or exposing it again

on the demand of a player. The cross-shaped tray, too, enables me to use for confining the 65 cards, simple elastic endless straps or rubber bands, such as are sold at the stationers and which, comparatively, cost but little and are readily adjusted to or removed from their places, thus avoiding delay and annoyance. 70 The branches of the tray may be made of any reasonable length, to bring the card receptacles near the players and yet the tray be very light. The cards, too, are well protected by the raised border of the tray, against 75 injury when a series of trays are piled upon one another or shuffled, and the cards and counters are prevented from sliding and rolling around the table. The cross-shaped tray naturally provides four small card receptacles 80 with a minimum weight of tray. I propose to pack the series of trays in a suitable box. When "in play" the trays would be removed from the box and placed in a pile within easy 85 reach, tray No. 1 being on top, tray No. 2 next, and so on. As fast as disposed of, the trays would be set into the said box edgewise, from which they would afterward be taken indiscriminately, to be played a second time. This dispenses with the necessity of "shuffling" 90 the trays. Score-cards or a score-book and the "counters," may also be suitably packed in the unfilled angles of the box. Convenient "counters" are the usual round disks called "poker chips" and if represented on the 95 drawings would be seen piled on the center portion of the trays.

Having thus fully described my invention, I claim as new and desire to secure by Letters Patent—

1. An apparatus for playing duplicate whist, comprising a cross-shaped tray having a raised border with its open top card receptacles within the branches projecting outward from the center portion thereof, and provided at or near the inner ends of the said branches with inwardly extending projections adapted to confine the cards in a given direction with freedom for removal when required, and means for holding the cards in said receptacles, substantially as described. 105

2. The cross-shaped tray for playing duplicate whist, consisting of a center or body portion for the counters, and branches forming card receptacles projecting outward from said center portion, and provided with a raised border having slots in their sides adapted to hold an endless and elastic strap or band for retaining the cards in their receptacles, in combination with projections at or near the inner ends of the branches, substantially as specified and for the purpose herein set forth. 115

JOHN G. BUTLER.
